UNITED STATES PATENT OFFICE.

JOSEPH T. SCHLESINGER, OF NEW YORK, N. Y., ASSIGNOR, BY MESNE ASSIGNMENTS,
TO UTILITY SAFETY APPLIANCE CORPORATION.

DOOR LOCK FOR ELEVATORS.

Application filed April 19, 1921. Serial No. 462,676.

To all whom it may concern:

Be it known that I, JOSEPH T. SCHLESINGER, a citizen of Hungary, and resident of the city of New York, in the county of 5 New York and State of New York, have invented certain new and useful Improvements in Door Locks for Elevators, of which the following is a specification.

The present invention relates to improvements in door-locks for elevators, and more particularly to a door-lock which controls, by the position of the door, the elevator motor mechanism.

In some devices of this type, the door-lock includes a casing, in which spaced apart contact plates are provided, the gap between said contact plates being bridged over by a metallic member, which is actuated by a slide bar on the door. These mechanisms have been found objectionable for the reason that an electric arc is apt to be formed between said contact plates when the metallic member is withdrawn therefrom, with the result that the motor may 25 be started with the door in open position.

One of the objects of the present invention is to overcome this defect by placing between the contact plates an arc extinguisher, which is directly controlled by the 30 locking bar of the device.

Another object of the invention is to so devise the extinguisher that it serves at the same time as a means for indicating the fact when the elevator door is in its unlocked 35 position.

With these and other objects in view, which will more fully appear as the nature of the invention is better understood, the same consists in the combination, arrangement 40 and construction of parts hereinafter described, pointed out in the appended claim and illustrated in the accompanying drawings, it being understood that many changes may be made in the size and proportion of the several parts and details of construction within the scope of the appended claim, without departing from the spirit or sacrificing any of the advantages 45 of the invention.

One of the many possible embodiments 50 of the invention is illustrated in the accompanying drawings, in which:—

Figure 1 is a front elevation, partly in section, of a door-lock constructed in accordance with the present invention, the

front cover of the lock casing being removed to show the interior construction; Fig. 2 is a side elevation thereof; Fig. 3 is an elevation similar to the one shown in Fig. 1 of the drawings of the lock casing, with the elements in other positions; and Fig. 4 is a section taken on line 4—4 of Fig. 1.

In the drawings, the numeral 10 indicates a casing of any suitable construction, adapted to be fastened to the door frame 65 of an elevator, for instance, by screws passing through lugs 11 thereon. This casing is provided with a detachable front plate 12. In the bottom 13 of the casing is formed an opening 14, through which a locking bolt, carried by the elevator door, may be projected into the casing. The bottom 13 includes two slanting portions 15, which converge toward the opening 14, for a purpose hereinafter to be described. 70 From the back plate 16 of the casing extends outwards a projection 17, having an inclined face 18, slanting toward the said opening. The purpose of this arrangement 75 will appear hereinafter.

Within the casing are mounted two insulating blocks 19, one on each side of the opening 14, and to these blocks are fastened, for instance by screws 20, metallic contact plates 21, forming part of a switch. 80 The contact plates are, preferably, made in the form of blade springs, extending substantially vertically, their lower ends being free and in operative relation to the opening 14 in the casing bottom. The contact plates are inserted into the motor control circuit of the elevator, conductors leading to the screws 20, in contact with the plates 21.

On the elevator door is mounted a vertically extending locking slide bar 22, movable in guides 23, of which only one is shown in the drawings, said guides being securely fastened to the door. The upward movement of the slide bar is limited by a washer 24 thereon, said washer abutting against the underface of one of the said guides. The slide bar is, preferably, tubular and carries at its upper end a head 25, on which is mounted an insulating block 26, carrying a metallic plug 27, that is adapted to be inserted between the contact plates 21. The plug is provided with an anti-friction ball 28, adapted to co-operate with the slanting portions 15 or the inclined face 18 of the 105 110

projection 17, as the case may be. The head 25 fits the opening 14 in the casing bottom.

On the front face of the insulating blocks 19 is slidably arranged an insulating body 29, in the form of a plate member, that is provided on its rear face with a rib 30, fitting into the gap between the metallic plates 21. On the front face of the insulating body may be printed or otherwise provided the 10 word "Open," which appears through an aperture 31 in the front plate 12 of the lock-casing when the head of the slide bar is withdrawn from the lock-casing. When this 15 head is inserted into the lock-casing, the insulating body 29 rests upon the anti-friction ball 28, the latter holding the said body in its elevated position, whereby the word "Open" is out of registering position with the aperture 31.

20 The operation of the device is as follows: When the elevator door is in its closed position, the slide bar 22 projects into the lock-casing, its plug 27 bridging the gap between the contact plates 21 and thereby completing 25 the motor control circuit. The locking bar, being projected into the casing, holds the door in locked position. Assuming that the elevator door is of the sliding type and moves in the direction of the arrow marked 30 X in Fig. 1 of the drawings to opening position, it is obvious that, in order to open the door, first the slide bar must be shifted downwards in the direction of its longitudinal axis until it is completely disengaged 35 from the casing 10, after which the door may be moved in the direction of the arrow mentioned. When the bar is thus retracted from the casing, the motor control circuit is opened and the elevator cannot be 40 started until the door is again closed and securely locked. When the slide bar is so withdrawn, the insulating body 29 drops

by gravity onto the casing bottom, thereby extinguishing any possible electric arc that may be formed between the contact plates 45 21. In shifting the door toward closing position, the anti-friction ball 28 is brought into contact with one of the slanting portions 15 of the casing, which acts thus as a striker, the slide bar being shifted upwards 50 as soon as it is brought into alignment with the opening 14 in the casing bottom, whereby the motor control circuit is completed. By the same operation, the insulating body 29 is moved upwards, the word "Open" thereon being thus withdrawn from the aperture 31 in the casing. If the door is movable in a direction opposite to the arrow X, the opposite slanting portion of the casing 15 will 55 act as a striker, and, if the door is of the swinging type, the projection 17 will perform this function.

What I claim is:—

In a door-lock for elevators, the combination with a casing having an opening in its bottom mounted upon the door frame, of a locking slide bar on the elevator door, spaced apart contact plates within said casing in the motor control circuit of the elevator, a metallic plug carried by said slide bar for bridging the gap between said contact plates when said bar is projected through said opening into said casing, and an insulating body having a portion fitting the gap between said contact plates, said body being freely slideable in said casing and resting on said plug when the latter is withdrawn from said casing.

Signed at New York, in the county of New York and State of New York, this 9th day of February, A. D. 1921.

JOSEPH T. SCHLESINGER.
